UNITED STATES PATENT OFFICE.

CHARLES PAUL CLARK, OF OLEAN, AND CARL A. BJORNSSON, OF WELLSVILLE, NEW YORK, ASSIGNORS TO CLARK BROTHERS COMPANY, OF OLEAN, NEW YORK, A CORPORATION OF NEW YORK.

FUEL-INJECTION MECHANISM.

Application filed April 25, 1927. Serial No. 186,329.

This invention relates to an improvement in fuel injection mechanism, especially designed for an internal combustion engine.

One of the objects of the invention is to provide for the regulation of the fuel injection into the cylinder of an internal combustion engine controllable from the working lead which is placed on the engine so that for a light load the supply of fuel is automatically decreased but for a heavy load an increase in fuel is automatically provided. This is accomplished by a suitable governor connected with a fuel injection valve and regulated directly from the engine lay shaft.

15 A further object of the invention is to operate and control fuel injection mechanism directly from the engine lay shaft, which regulates the admission of fuel to the engine cylinders at properly timed intervals.

20 A still further object of the invention is to arrange the fuel inlet in alignment with and in the direction of the exhaust ports of the cylinder, so as to insure of a thorough mixing of the fuel with the air used in scavenging the cylinder. Compressed air only is used in the scavenging operation, and near the completion thereof the fuel injection valve is opened directly in the cylinder to admit the fuel into the path of the air so as to have a 30 thorough mixing thereof prior to the explosion.

25 In the usual type of two cycle gas engine, the charge (air and gas mixture) is precompressed to a few pounds above atmospheric pressure in a separate compression chamber. The expanded gases exhaust through cylinder ports uncovered by the piston near the end of the expansion stroke. When their pressure has fallen nearly to atmospheric pressure, the 40 precompressed charge enters through ports also uncovered by the piston and sweeps out the burned charge. The process of exhausting the burned gases, scavenging of the cylinder or admitting the fresh charge takes place 45 through a period representing about one-fifth of the length of the expansion stroke and through an equal length at the first part of the compression stroke. During this process of scavenging, a large percentage of the 50 charge is lost through the exhaust ports which are full open at the height of the scavenging period and remain open after this period is over, allowing a large percentage of the

fresh charge to escape into the exhaust line from the engine.

55 The space occupied by the gaseous fuel in the fresh charge is considerable and if compared with the cylinder volume, the ratio of this gas to air represents a proportionate amount in loss of engine output.

60 If fresh air only was precompressed for the scavenging operation, the excess air will sweep the cylinder and enter the exhaust line, thereby insuring more complete scavenging, greater economy, and higher engine output.

65 In the accompanying drawings:—

Fig. 1 is a plan view of the complete fuel injection mechanism, as applied to an internal combustion engine;

Fig. 2 is a top plan view of the main portion of the injection mechanism;

Fig. 3 is a vertical section partly in side elevation of the same;

Fig. 4 is a vertical section through the fuel injection valve;

Fig. 5 is a cross section on the line 5—5 of Fig. 3; and

Fig. 6 is an end view partly in section of the mechanism as applied to a twin engine.

70 As illustrated in Fig. 1, the fuel is drawn from any suitable source of supply, through a pipe 1 to the pump and compressor 2, which is operated by means of a suitable motor 3, and the fuel is forced from the compressor 2 through a pipe 4 to a supply tank 5.

75 A reducing valve 6 is interposed in the pipe 7 which extends from the supply tank 5 to the cylinder 8 for supplying the fuel thereto. This reducing valve 6 may be set to deliver the gaseous fuel at any suitable pressure desired, which will insure the most economical operation of the engine.

80 The internal combustion engine to which this fuel injection mechanism may be applied may be of any suitable form and construction and is designated generally by the numeral 9. The main drive shaft 10 of the engine 9 has the fly-wheels 11 fixed thereon, which are driven from the piston 12 operated in the cylinder 8. The manner of this drive is conventional and, being well understood, is not set forth in detail.

85 A lay shaft 13 is connected in any suitable manner with the drive shaft 10 to be rotated therefrom. The outer end of the lay shaft 13 100 is mounted in a bearing 14 supported by a

suitable bracket 15 carried by the engine housing. This bracket is provided with a cover 16. The lay shaft 13 has a cam 17 fixed thereon, as clearly shown in Fig. 5, in position to engage a roller 18 carried by a lever 19 pivoted as at 20 to a bracket or arm carried by the supporting bracket 15. The outer end of the lever 19 supports a push rod 21, the upper end of which engages a horizontal lever 22 carried by a shaft 23 mounted in bearings 24 in the cover 16.

The shaft 23 also carries a vertical arm 25 which is connected with a secondary push rod 26, as shown in Fig. 3. The outer end of the push rod 26 is operatively connected with one end of the valve lever 27 pivoted as at 28 in a bracket 29 carried by a valve casing 30. As shown in Fig. 4, the opposite end of the lever 27 is connected with a valve stem 31 which carries a valve 32 in position to engage a valve seat 33 in the casing 30. The valve stem 31 has a disk 34 fixed thereon, and a spring 35 is interposed between this disk 34 and the casing 30. The interior of the casing 25 communicates with the supply pipe 7 and receives a charge of fuel therefrom.

As shown in Fig. 3, a spark plug 36 is placed in the center of the end cover of the cylinder 8, and said spark plug is suitably connected with a magneto 37. The valve casing 30 is secured to the end of the cylinder 8 on one side of the spark plug 36. The gaseous fuel is discharged from the casing 30 about the valve 32 when unseated in a direction at an angle to the center axis of the cylinder 8, and in the general direction of the exhaust ports 38 arranged in one side of the cylinder in position to be covered and uncovered by the piston 12.

Arranged on the opposite side of the cylinder from the exhaust ports 38 is an air port 39, through which compressed air is supplied to the cylinder for the scavenging operation. This port is likewise adapted to be covered by the piston, and on the side next to the port 39 the piston 12 is provided with the shoulder 40 in position to direct the compressed air in an upward direction toward the fuel injection valve 32. It will be noted that the fuel injunction valve is on the same side of the cylinder with the compressed air inlet port, although the fuel valve is in the end of the cylinder but at one side of said end, and the exhaust ports are arranged on the opposite side of the cylinder.

For automatically controlling the supply of fuel through the pipe 7 to the cylinder, a governor, designated generally by the numeral 41, is used. This governor may be of any suitable construction but operates to control a valve stem 42 connected with suitable valve mechanism for automatically regulating the passage of fuel through the pipe 7. The governor is operated by beveled gears 43, one of which is mounted on a shaft 44.

The opposite end of the shaft 44 carries a pinion 45 meshing with a gear 46 fixed on the outer end of the lay shaft 13. The governor housing 47 is supported by a plate 48 carried by the supporting bracket 15.

In the operation of the machine, the gas or fuel is pumped into the tank 5 by the compressor 2 from where it passes through the reducing valve 6 and the pipe 7 into the cylinder 8. The lay shaft 13 being rotated by the main drive shaft 10 of the internal combustion engine causes a rotation of the governor 41 through the gearing 43, 45 and 46, and the shaft 44, and as the speed of the drive shaft 10 and likewise of the governor 41 increases, it will tend to force the valve stem 42 downward, tending to close the valve and shut off the passage of fuel through the supply pipe 7. This governor therefore regulates the passage of gaseous fuel to the injection valve in quantities proportionate to the particular engine load.

When the engine is operating under a light load, the speed is highest which, as stated forces the valve stem 42 downward to decrease the gas supply through the pipe 7. When the engine is operating at maximum load, the speed is less and the valve stem 42 is therefore elevated to admit more fuel through the supply pipe 7.

The rotation of the lay shaft 13 from the drive shaft 10 causes a rotation of the cam 17, which rocks the lever 19 on its pivot 20, causing a periodical longitudinal movement of the push rod 21 and by reason of the bell-crank levers 22 and 25 mounted on the shaft 23 causes a similar longitudinal movement of the push rod 26, which, in turn, rocks the lever 27 and periodically moves the valve stem 31 inward against the tension of the spring 35 to unseat the valve 32 for admitting a supply of fuel into the cylinder 8. The position of the injector valve 32 is most advantageous and, as stated above, it is arranged at the opposite side of the cylinder from the exhaust ports 38 and in position to direct the discharge of fuel into the cylinder substantially in the direction of the exhaust ports. Fresh air only is used in the scavenging operation to force out the exhaust gases from the cylinder through the exhaust ports 38. This fresh air is precompressed and admitted to the cylinder through the port 49 during the back stroke of the piston and a portion of the return stroke, which uncovers this port, allowing the air to pass in and through the cylinder to force out the exhaust gases on the return stroke of the piston.

When the ports are partly closed, as shown in Fig. 3, the valve 32 is moved from its seat 33 to allow the injection of gaseous fuel into the cylinder. The shoulder 40 directs the air toward the injection valve 32 and during this forward motion this compressed air picks up the gaseous fuel which had just been

admitted, resulting in an intimate mixture of gas and air. The motion of the mixture, when reaching the bottom of the cylinder, is deflected inward again, resulting in a revolving mass and insuring of complete mixture of the fuel and air. The fuel injection is completed when the working piston has traveled about forty-five percent of the compression stroke, at which point the pressure in 10 the cylinder and in the injection valve are about balanced.

In this manner, compressed air only is used for the scavenging operation and the fuel is admitted directly into the cylinder for 15 mixture with the air at the close of the scavenging operation, which insures of a thorough mixing of air and gaseous fuel. The relation of the injection valve, the compressed air port 39, shoulder 40 and exhaust ports 38 20 insures of this thorough mixing operation.

In the use of the invention as applied to a twin engine, as shown in Fig. 6, each of the cylinders 49 is provided with the injection valve mechanism operated by the levers 27 25 and push rods 26. A cross shaft 50 is actuated by gears 57 from the lay shaft 13, and this lay shaft 13 carries suitable cams for imparting motion to the push rods 26. The operation is otherwise the same in connection 30 with the twin engine, as set forth above for the two cycle engine.

We claim:—

1. In a device of the character described, the combination with an internal combustion 35 engine and cylinder therefor, of a lay shaft connected with and operated by the engine, a cam fixed on said lay shaft, a rocking lever in position to be actuated by said cam, bell-crank levers connected with and actuated by 40 the rocking lever, a valve stem carrying a control valve connected with the cylinder for controlling the admission of fuel thereto, a rock arm connected with the valve stem, and a push rod transmitting motion from the 45 bell-crank levers to the last-mentioned rock arm.

2. In a device of the character described, the combination with an internal combustion engine, and means for admitting fuel thereto, of a cam actuated rocking lever connected 50 with the engine, a push-rod operated by said rocking lever, a bell-crank connected with said push-rod and a second push-rod interposed between and for transmitting motion from the bell-crank to the fuel admitting 55 means.

3. In a device of the character described, the combination with an internal combustion engine and means for admitting fuel thereto, 60 of a casing carried by the engine, a lay shaft mounted in a bearing in said casing, and having a cam thereon, a rocking lever pivotally mounted in the casing and actuated by said cam, a cover for the casing, a bell-crank lever mounted on the cover, a push-rod interposed 65 between the bell-crank lever and the rocking lever, and a second push-rod interposed between and for transmitting motion from the bell-crank lever to the fuel admitting means.

4. In a device of the character described, 70 the combination with a valve, of a cam actuated rocking lever, a push rod operated by said rocking lever, a bell-crank connected with the push rod, and a second push rod interposed between and for transmitting motion 75 from the bell-crank to the valve.

5. In an internal combustion engine, the combination with a cylinder, a valve for regulating the admission of fuel thereto, a source of fuel supply communicating with the valve, 80 a governor controlled valve interposed between the source of fuel supply and the first-mentioned valve, a lay shaft operated by the engine, and geared to and for actuating said governor controlled valve, cam actuated levers controlled by said lay shaft, and a push rod connected with said cam actuated levers 85 for actuating the first-mentioned valve.

In testimony whereof we affix our signatures.

CHARLES PAUL CLARK.
